UNITED STATES PATENT OFFICE.

WILLIAM W. LEWIS, OF ONEIDA, NEW YORK, ASSIGNOR OF ONE-HALF TO CHARLES E. B. WILLIAMS AND WILLIAM J. CAPRON, OF ONEIDA, NEW YORK.

TROLLING-SPOON.

1,062,980.

Specification of Letters Patent.

Patented May 27, 1913.

Application filed August 23, 1912. Serial No. 716,714.

To all whom it may concern:

Be it known that I, WILLIAM W. LEWIS, a citizen of the United States, residing at Oneida, in county of Madison and State of 5 New York, have invented certain new and useful Improvements in Trolling-Spoons, of which the following is a specification.

My invention relates to an improvement in trolling spoons, and the object is to provide means whereby the spoon can be removed and applied readily.

The invention consists of certain novel features of construction and combinations of parts which will be hereinafter more fully 15 described, illustrated and claimed.

In the accompanying drawings Figure 1 is a view in front elevation showing my invention applied; Fig. 2 is a view in side elevation; Fig. 3 is a vertical sectional view.

20 A represents a wire upon which is mounted a spring frame 1. The spring frame is preferably made angular or L-shaped and the ends are provided with openings through which the wire A extends. The frame is 25 capable of sliding and rotary movement on the wire and is provided with a button 3 which is movably mounted thereon.

A spoon C, which can be made of any 30 shape and color, is provided with a notch 4 at one end, the notch being of greater size at its inner end and adapted to be slid over the spring frame at the end of the spring frame which is in closest proximity to the wire A. That is, the notch 4 fits around the 35 wire A, and the spoon is then drawn along the wire until the notch 4 comes into engagement with an end of the spring frame 1, when the spoon will leave the wire and the notch will engage the spring frame thereby 40 connecting the spoon to the spring frame.

An elongated slot 5 is formed in the body of the spoon through which the button 3 protrudes and which button is turned after it has passed through the slot for fastening 45 the spoon to the spring frame. The L-shaped frame causes the spoon to be held away from the wire and allows it to have free movement along the wire. The spring frame also allows the spoon to close inward 50 on the wire when the fish takes hold of it

so that the hooks 5 which are connected to one end of the wire A will be in a better position to hook the fish. The usual line, not shown, is connected to the other terminal of the wire A.

55

It will be seen from the foregoing that I can apply spoons at any time without the necessity of removing the hooks or disconnecting the line by simply turning the button and allowing the spoon to be raised from 60 the frame and then withdrawing the notched end from the spring frame which allows the spoon to be removed and when the spoon is to be applied the notched end is first inserted over the spring frame and then the button is passed through the elongated slot in 65 the spoon and then turned for fastening the spoon to the spring frame.

Having thus described my invention, what I claim as new and desire to secure by Letters Patent is—

1. In a trolling spoon, the combination with a wire, of a flexible frame loosely mounted upon a wire, a spoon having a notch formed therein adapted to fit about 75 the flexible frame for fastening the spoon to the frame and means for fastening the spoon to the frame.

2. In a trolling spoon, the combination with a wire, of a flexible frame loosely 80 mounted upon the wire, a spoon having a notch formed therein adapted to fit about the flexible frame for fastening the spoon to the frame, said spoon having an elongated slot therein and a button movably mounted 85 upon the flexible frame adapted to be passed through the slot in the spoon and then turned for fastening the spoon to the frame.

3. In a trolling spoon, the combination with a wire, of an L-shaped spring frame 90 having openings therein at the ends through which the wire extends, a spoon having a notch formed in one end thereof adapted to engage the spring frame, said spoon having a slot formed therein, and a button on the 95 frame adapted to pass through the slot for fastening the spoon to the frame.

4. In a trolling spoon, the combination with a wire, of a frame mounted upon the 100 wire, and a spoon having a notch therein

for fastening the spoon to the frame, said notch adapted to fit about the wire and the spoon drawn along the wire so that the notch passes onto and engages with the
5 frame for connecting the spoon to the frame and means for fastening the spoon to the frame.

In testimony whereof I affix my signature, in the presence of two witnesses.

WILLIAM W. LEWIS.
